UNITED STATES PATENT OFFICE

106,594

DESIGN FOR AIR CONDITIONING APPLIANCE OR SIMILAR ARTICLE

Robert Heller, New York, N. Y., assignor to The A. C. Gilbert Company, New Haven, Conn., a corporation of Maryland

Application August 13, 1937, Serial No. 71,063

Term of patent 14 years

To all whom it may concern:

Be it known that I, Robert Heller, a citizen of the United States, residing at New York, in the county of New York and State of New York, have invented a new, original, and ornamental Design for an Air Conditioning Appliance or Similar Article, of which the following is a specification, reference being had to the accompanying drawing, forming part thereof.

Figure 1 is a front elevation, Figure 2 is a side elevation and Figure 3 is a perspective view of an

air conditioning appliance showing my new design. Figure 4 is a plan view of the base in its visible portions, and Figures 5, 6, and 7 are sectional views showing contours of the base on the section planes 5—5, 6—6, and 7—7, respectively, in Figure 4.

I claim:

The ornamental design for an air conditioning appliance or similar article substantially as shown and described.

ROBERT HELLER.
